LEVIS MILLER BOOTH, OF PLAINFIELD, NEW JERSEY.

PROCESS OF MANUFACTURING PULP OR PAPER.

Application filed February 14, 1923. Serial No. 618,965.

To all whom it may concern:

Be it known that I, LEVIS MILLER Booth, a citizen of the United States, residing at Plainfield, in the county of Union, State of New Jersey, have invented certain new and useful Improvements in Processes of Manufacturing Pulp or Paper.

This invention relates to the process of manufacturing pulp or paper on a Four-drinier or other paper machine where the stock is suspended in water and is applied to a screen. By the process heretofore in use a substantial portion of the fibre and loading material, if any of the latter was used, together with nearly all of the water which passes through the screen was either wasted or went to a save-all or a sedimentation pulp saver. The sedimentation pulp saving equipment heretofore employed was of low efficiency for many types of white water in that it permitted a considerable portion of the pulp to flow off to waste along with the partly clarified water, and the pulp which settled at the bottom of the tank became partially felted on the bottom of the tank with the result that the thickened pulp effluent drawn from the bottom of the tank was not of uniform consistency and therefore could not be advantageously returned directly to the paper machine, as is desirable.

In my recent United States Letters Patent No. 1,443,454, dated January 30th, 1923, is disclosed a process of chemical coagulation adapted to insure a high degree of clarity of the top effluent water. My present process includes not only the chemical process above referred to, but in addition thereto provides for a further step in the treatment of the white water which renders approximately 90 per cent of the pulp recovered from the white water suitable for immediate reuse on the paper machine.

The first step in my present process consists in applying to the white water from the paper machine two or more chemical reagents which will produce a flocculent precipitate and therefore assist in the sedimentation, as is described in my said Letters Patent. Sulphate of aluminum and sodium carbonate are among the reagents suitable for this purpose.

The second step consists in delivering the white water to which such chemical treatment has been or is then applied to the

lower portion of a sedimentation tank which is equipped with a slowly moving agitator traveling near the bottom of such tank and at such speed that there will be no appreciable interference with the sedimentation of the pulp or the clarity of the water in the upper portion of the sedimentation tank.

Third, after the pulp has accumulated by sedimentation in the lower portion of the pulp saver tank for a period which is usually less than one hour from the starting of the paper machine, the outlet valve located near the bottom of said tank is opened to such an extent that the thickened pulp may then be delivered in a continuous stream to the paper machine or elsewhere for use or to a storage tank.

In practicing this process it is easily possible to control the withdrawal of the thickened pulp or total paper making materials so that approximately 90 per cent of the paper making materials in the white water will be withdrawn through the thickened pulp outlet from the lower portion of the tank in condition to be supplied to the paper machine.

The application of a suitable coagulant to the white water together with the continually slow moving agitator has the effect of maintaining a high degree of uniformity in the consistency of the paper making materials. Preferably, the speed of the agitator is about three feet per minute and when the agitator is moved at this speed and the valve controlling the outlet near the bottom of the tank properly regulated, the thickened pulp flowing from the tank is suitable for use on the paper machine.

From a higher point in the tank, usually four or more feet above the bottom, water for the beaters or for other uses is withdrawn from the pulp saver sedimentation tank from time to time, as required. In practice eight or nine per cent of the pulp contained in the white water is drawn from the upper level just referred to. The surplus of water, if any, may be drawn from near the top of the tank. Due to the influence of gravity assisted by the chemical coagulation approximately ninety per cent of the pulp falls to the lower portion of the sedimentation tank. The result is that the clarified effluent taken from the top of the tank usually contains only one to two per cent of the pulp.

per cent of the amount of pulp carried by the white water fed to the sedimentation tank.

Referring to the drawing, Figure 1 is a plan view of a sedimentation tank and Figure 2 a section on the line XX of Figure 1. Similar numerals refer to similar parts throughout the various views.

In the accompanying drawing, 1 designates the sedimentation tank which is preferably ten feet or more in depth, 2 the slow moving agitator, 3 a pipe communicating with the tank near the bottom thereof through which the thickened pulp is discharged, 4 a valve serving to cut off or regulate the flow of thickened pulp from the tank through the pipe 3, 5 is a pipe communicating with the tank preferably four or more feet from the bottom thereof, 6 is 10 a valve adapted to cut off or regulate the flow of liquid from the tank through the pipe 5, 7 is a circumferential launder into which the surplus water which usually contains from one to two per cent of the pulp 15 contained in the white water supplied to the tank is discharged from the tank 1 through the pipe 8, for conveying said water to any desired point in the paper mill or elsewhere, 9 is the inlet pipe by which white 20 water is supplied to the tank 1. The white water from the pipe 9 is discharged into the centrally located box 10, the open and lower end of which is located, as shown, some distance above the bottom of the tank 25 1 and the agitator 2, the dimensions of the box 10 being such that the flow of white water is not sufficiently rapid to cause disturbing eddies or currents which will interfere substantially with the sedimentation in 30 the tank 1.

Claims.

1. The process of manufacturing pulp or paper consisting of reclaiming for reuse the solid particles in the white water by the 45 addition thereto of such reagents as will assist by coagulation in the sedimentation of the solid particles, permitting the solid par-

ticles to settle by sedimentation to the bottom of a sedimentation tank, gently agitating the liquid in the sedimentation tank by 50 means of a slowly traveling agitator traveling near the bottom of the sedimentation tank, discharging the thickened pulp from the lower portion of the tank and the surplus liquid from a plurality of higher levels 55 as required.

2. The process of manufacturing pulp or paper consisting of reclaiming for reuse the solid particles in the white water by the addition thereto of such reagents as will assist by coagulation in the sedimentation of the solid particles, permitting the solid particles to settle by sedimentation to the bottom of a sedimentation tank, gently agitating the liquid in the sedimentation tank 60 by means of a slowly traveling agitator traveling near the bottom of the sedimentation tank and discharging the thickened pulp from the lower portion of the sedimentation tank in condition to be added to 65 the pulp supplied to the paper machine and discharging the surplus liquid from said tank at a plurality of higher levels as required.

3. The process of manufacturing pulp or paper consisting of reclaiming for reuse the solid particles in the white water by addition thereto of such reagents as will assist by coagulation in the sedimentation of the solid particles, permitting the solid particles to settle by sedimentation to the bottom of a sedimentation tank, gently agitating the liquid in the sedimentation tank by means of a slowly traveling agitator traveling near the bottom of the sedimentation tank, discharging the thickened pulp from the lower portion of the sedimentation tank and so regulating the rate of discharge that the thickened pulp discharged from said tank will be in condition to be added to the 70 pulp supplied to the paper machine and discharging the surplus liquid from said tank at a plurality of higher levels as required.

LEVIS MILLER BOOTH.
